Primary Examiner — Selina Sikder(74) *Attorney, Agent, or Firm* — Mayer & Williams PC; Karin L. Williams(57) **CLAIM**

The ornamental design for a new bridge rectifier package with heat sink, as shown and described.

DESCRIPTION

FIG. 1 is a left, top perspective view of a new bridge rectifier package with heat sink showing our new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a back view thereof.

1 Claim, 2 Drawing Sheets*FIG. 1**FIG. 2**FIG. 3*

FIG. 4

FIG. 5

FIG. 6
